Primary Examiner — Martie K Holtje(57) **CLAIM**

The ornamental design for a handheld ultrasonic bark controller, as shown and described.

DESCRIPTION

FIG. 1 is a front left perspective view of a handheld ultrasonic bark controller

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The structural features depicted by broken lines have been shown for the purpose of illustrating portions of the handheld ultrasonic bark controller that form no part of the claimed design.
